UNITED STATES PATENT OFFICE.

CHARLES A. RANDALL, OF NEW YORK, N. Y.

TELEPHONIC TRANSMITTER.

SPECIFICATION forming part of Letters Patent No. 295,805, dated March 25, 1884.

Application filed May 3, 1883. (No model.)

To all whom it may concern:

Be it known that I, CHARLES A. RANDALL, a citizen of the United States, residing at New York, in the county and State of New York, 5 have invented new and useful Improvements in Telephonic Transmitters, of which the following is a specification.

This invention relates to improvements in that class of telephonic transmitters known as "lever-transmitters," in which the vibrations of the diaphragm are transmitted to the current-varying contacts by means of an amplifying-lever. In transmitters of this class as heretofore constructed and provided with 10 metallic diaphragms which expand and contract with variations of temperature, or diaphragms formed of material which is affected by the hygrometric condition of the atmosphere, there has been experienced great difficulty in maintaining a proper adjustment of 15 the contact point or points upon which the lever acts, from the fact that a very slight expansion or contraction of the diaphragm with which the short arm of the lever is connected causes an amplified movement at the tip of 20 the long arm, which destroys effectually the relation in position which is necessary between said tip and the contact point or points upon 25 which it acts. In overcoming this difficulty, 30 the first part of my present improvement consists in the combination, with the amplifying-lever, of a motive diaphragm formed of a carbon or slate disk, whereby the diaphragm will not be expanded or contracted by variations 35 of temperature, and hence not throw the lever out of proper relation to the circuit-varying contacts upon which it is to act.

My invention also consists in certain improved details of construction for promoting 40 efficient action of transmitters of this class, as will be hereinafter particularly described, and pointed out in the appended claims.

In the accompanying drawings, Figure 1 is 45 a side elevation of a telephonic transmitter constructed according to my invention. Fig. 2 is a rear view of the same. Fig. 3 is a side view, partly in elevation and partly in section on the line $\alpha\alpha$ of Fig. 2. Fig. 4 is a sectional view, illustrating a modification of the devices 50 for regulating the tension of the contact-points

upon which the lever acts. Fig. 5 is a side elevation of a transmitter having a modified arrangement of amplifying-lever and contacts.

The letter A indicates a diaphragm-supporting block, which is secured to and projects 55 rearwardly from the front wall, b, of the casing B. The inner end of this block is recessed to receive a metallic disk, I, having a central opening, as at i, the diaphragm D being secured at the rear of I and at its margin or 60 edge by a suitable clamping-ring, d, through which screws take into the body of the block A.

E indicates the ordinary mouth-piece, which is secured to the front wall of the casing around 65 a suitable opening, from which a funnel-shaped passage, E', extends through the block A, and terminates inwardly at the opening in the disk I. The diaphragm-supporting block A being of insulating material and of not very great 70 vibratory quality, the disk I, of vibratory material, is recessed therein, in order to convey as strongly as possible to the diaphragm such vibrations as strike and expand themselves upon the sides of the opening in A, instead of 75 being conveyed directly through the opening in the disk to the diaphragm. By the described construction of the diaphragm-supporting block A and disk I, a chamber is formed in front of the diaphragm and between 80 it and the mouth-piece, by which a considerable body of air is maintained in front of the diaphragm, and serves as a cushion to re-enforce the action upon the diaphragm of the sound-vibrations which are projected against 85 it through the opening in the disk. The diaphragm D is made of carbon or slate, or any material having similar characteristics, for the purpose hereinbefore stated.

F is the amplifying-lever, made preferably 90 of wood or other light non-conducting material, and fulcrumed on a cross-bar, d', secured to the ring d. The upper end of the short arm f of this lever is connected loosely to a stud, d'', which is secured to and projects 95 rearwardly from the center of the diaphragm, a pin, d'', being secured to the stud and passing loosely through an opening, o, in the lever. The lower long arm, f', of the lever is terminated by a small cylinder of car- 100

bon, f^2 , which is connected by an insulated wire, f^3 , with the metallic bearings of the lever. On opposite sides of the middle carbon cylinder are arranged elastic contact-terminals 5 G and G' of the battery-circuit. Each of these terminals consists of a carbon contact-piece, g , carried at the end of a sliding rod, g' , which has its bearings in a standard, g^2 , secured to an adjustable base, g^4 , and in a socketed adjusting-screw, g^5 , arranged in the top of another standard, g^6 , which is also secured to said adjustable base.

On the rod g' , behind the standard g^2 , is a shoulder, S, against which bears one end of a spiral spring, which surrounds the rod and has its other end bearing against the tip of the socketed adjusting-screw g^5 .

From the rear side of the carbon contact-piece of the contact-terminal G projects a pin, 20 h , which passes loosely through an opening in the standard g^2 , and serves to prevent said contact-piece and its supporting-rod from turning, as such turning might vary the adjustment of the contact-piece, owing to lack 25 of trueness of its surface or slight bending of its supporting-rod.

From the carbon contact-piece of the contact-terminal G' projects an arm, g^6 , the lower end of which has an opening, through which 30 loosely passes a headed screw, g^7 , which takes into the standard g^2 , which supports the said contact-piece and its rod. It will be observed that by adjusting the screw g^7 I may regulate the extent of the movement of the contact-piece 35 toward the carbon cylinder of the lever, and I am thus enabled to regulate the relation between this contact-piece and the carbon cylinder of the lever when said lever moves toward the other contact-piece. The adjustable bases g^4 g^4 slide in separate metallic guides g^8 , and are adjusted therein by means of adjusting-screws g^9 , which project from each of the standards g^6 , and are provided with adjusting-nuts g^{10} , arranged between stationary 45 lugs g^{11} . The contact-terminals, their supports, base-guides, and adjusting devices are all supported by a non-conducting base-plate, k , which is carried by an arm, L, projecting downward from and secured to the disk I. By 50 this arrangement I secure a common support for the diaphragm, the lever, and the contact devices, which I find to be very advantageous, as there is less liability of the parts getting out of adjustment than when they are 55 separately supported. The contact-terminals G and G' are to be electrically connected with the opposite poles of a battery, as indicated at N, by wires w w , which lead from the metallic guides, in which slide the metallic supporting devices of the said terminals. The 60 center of the battery is connected to the ground. The contact carbon cylinder f^2 of the amplifying-lever is connected by the wire f^3 , the metallic lever-bearings, metallic cross-bar d^3 , and a wire, f^4 , with the line-wire direct or to the primary of an induction-coil, in

the usual manner, the opposite terminal of the primary in such case being connected to the ground or with the center of the battery, which then need not be connected with the ground. 70

This transmitter operates generally in the same manner as that shown and described in my Letters Patent No. 235,019, granted November 30, 1880, and may be used in connection with any of the ordinary magneto-receiving telephones. 75

In the modification shown in Fig. 4 the rods which carry the battery-terminals G and G' abut at their rear ends against flexible dia-phragms, which form walls of mercury-cups m m , provided with adjusting-screws m' , which may be adjusted into the mercury and cause the same to exert more or less tension on the said flexible diaphragms, as desired, for adjusting the resistance of the contacts to the action of the lever. In this modification the springs are omitted, the elastic diaphragm serving in lieu thereof. 85

In the modification shown in Fig. 5 the amplifying-lever F' is fulcrumed at its upper end and intermediately connected with the stud which projects from the diaphragm D. To the same pin which supports the lever are pivoted pendent metallic arms p p' , which are insulated from said pin, said arms being arranged on opposite sides of the lever F', and having their lower ends bent toward the contact-cylinder carried by said lever, and provided with carbon contact-pieces q q' , arranged to come in contact with the opposite ends of said cylinder, respectively. The pendent arms may be so shaped that their contact-pieces will come against the contact-cylinder of the lever by gravity, and they may, besides, be connected by a spring, s, and adjusting-screw s' , provided with a thumb-nut, s^2 , so that the pressure of the contact-pieces upon the cylinder may be regulated. The upper ends of the arms p and p' may be connected by suitable wires, w w' , with the opposite poles of a battery, and the lever F' may have its contact-cylinder connected with the main line or an induction-coil by means of an insulated wire, f^4 . In this modification it will be seen that the current-varying contacts are supported independently of springs, and the vibrations of the lever are taken off by contact-points necessarily moving in unison therewith and in the same circle. When the instrument is not in use, the battery-current flows through the two arms P P, their contact-pieces, and the contact-cylinder of the lever; but when the diaphragm is set in motion the pressure of the contact-cylinder upon the contact-pieces of the arms is so varied, increasing upon one while decreasing upon the other, that the battery-currents of opposite polarity are alternately directed over the wire f^4 , which connects the contact-cylinder of the lever with the main line or induction-coil. 115 120 125 130

No claim is made herein to the construction shown in Fig. 5, although it embodies and car-

ries into effect the general principle hereinbefore laid down. It will be made the subject of a separate application.

Having thus described my invention, what 5 I claim is—

1. In a lever transmitting-telephone, the combination, with the amplifying-lever, of a motive diaphragm formed of a carbon or slate disk, substantially as described.
- 10 2. In a telephonic transmitter, the combination, with the motive diaphragm, of a mouth-piece and an air-chamber interposed between the diaphragm and mouth-piece, said air-chamber being conical in form, its greater diameter 15 being next to and larger than the inner opening of the mouth-piece, substantially as described.
- 20 3. The combination, with the diaphragm, of the amplifying-lever loosely connected therewith, to have a slight play independently of the diaphragm, substantially as described.
- 25 4. The combination, with the amplifying-lever and its carbon or contact terminal and the battery terminals or contacts, of means, substantially such as described, for adjusting the positions of said battery-terminals relatively to each other and the lever-terminal,

and separate means, substantially such as described, for adjusting their normal contact or pressure, substantially as set forth.

5. The combination, with a spring-seated battery-terminal, as shown and described, of a pin or equivalent means attached to the carbon and to its support, so as to prevent the carbon from turning in its seat or support, 35 substantially as set forth.

6. The combination of the air-chamber, the metallic disk attached thereto, the diaphragm, the lever supported from the air-chamber, block and disk, a non-conducting base-plate 40 carrying the battery-terminals, and an arm or support rising from and carrying or supporting the air-chamber block and disk, and forming a common support for the operative devices attached to or controlled by the motive 45 diaphragm, substantially as described.

In testimony whereof I have hereunto set my hand in the presence of two subscribing witnesses.

C. A. RANDALL.
